UNITED STATES PATENT OFFICE.

SPENCER OTIS, OF CHICAGO, ILLINOIS.

STEAM-LOCOMOTIVE.

SPECIFICATION forming part of Letters Patent No. 683,658, dated October 1, 1901.

Application filed March 21, 1901. Serial No. 52,179. (No model.)

To all whom it may concern:

Be it known that I, SPENCER OTIS, a citizen of the United States, residing at Chicago, in the county of Cook and State of Illinois, have 5 invented certain new and useful Improvements in Steam-Locomotives, of which the following is a specification, reference being had therein to the accompanying drawings.

This invention relates to the construction 10 of the front end or smoke-box of locomotives and to the extension of said smoke-box to inclose the cylinders and steam-chests thereof within said smoke-box.

The object of my invention is to provide 15 said smoke-box with passages around the cylinders through which the hot gases and products of combustion are directed under and around said cylinders to keep them hot and prevent condensation of steam therein.

20 It relates also to means of regulating the amount of hot gases circulating around said cylinders and steam-chests.

The invention will first be described in connection with the accompanying drawings, in 25 which—

Figure 1 is a transverse vertical section of a locomotive smoke-box constructed in accordance with my invention. Fig. 2 is a longitudinal vertical central section of the same. 30 Fig. 3 is a horizontal section of the same on line $\alpha\alpha$ of Fig. 1. The hot gases indicated by arrows in each figure show the hot currents descending close to the walls of the smoke-chamber and ascending in its center alongside of the exhaust-nozzle. Figs. 4, 5, 35 and 6 represent a modification of the smoke-box. Fig. 4 represents a transverse vertical section, Fig. 5 a central longitudinal vertical section, and Fig. 6 a horizontal section of the 40 same on line yy of Fig. 4. The arrows in each figure indicate the current of hot gases descending between the cylinders within the smoke-box, passing under said cylinders, and ascending alongside of the cylinder-walls and 45 between said walls and the walls of the extension of the smoke-chamber.

In said drawings, A represents the body of a tubular boiler of any suitable construction, and C the smoke-box thereof, which is of 50 larger diameter than usual and contains the steam-cylinders D, one of which is shown provided with a valve-cylinder d for a piston-

valve and the other with a steam-chest c for a slide-valve. The steam-pipes leading from the boiler to the steam-chests are shown at E, 55 and their lower ends are secured to the steam-chests. The cylinders are supplied with saddles F, as usual, which saddles have a central opening f for the passage of the exhaust-nozzles G and of the hot gases alongside of 60 said nozzles and direct them to the smoke-stack H. The length of the smoke-box is preferably the same as that of the cylinders, so that it can be secured to the flange of the cylinder-heads, or it may be made to extend 65 over the cylinder-heads.

To regulate the proportion of hot gases which pass through the opening p and which are directed around the bottom of the steam-cylinders through the passages m, suitable 70 dampers h are located between the steam-chests and the horns of the saddle. In the drawings the dampers are shown pivoted to the steam-chest; but they may be pivoted to the horns of the saddle, or sliding dampers 75 may be used. The lower part of the smoke-stack H is also provided with a damper k, which may be opened to allow the hot gases to go direct from the flues to the stack.

The steam-chests and cylinders may be in- 80 closed in sheets i, of metal or of asbestos. As the lower part of the smoke-chamber acts as a cinder-box, hand-holes j are placed in the walls of said box, either in the ends, as shown, or in the bottom.

In the modification shown in Figs. 4, 5, and 6 there is placed in the smoke-box a plate K, which is nearly horizontal, but slightly inclined toward its front end. The rear end of said plate is secured to the tube-sheet of the 90 boiler slightly above said tubes to deflect downwardly the hot gases issuing from the tubes. They are thereby directed through openings l alongside of the exhaust-nozzle G downwardly between the two cylinders D, 95 through a passage m, under said cylinders, between them and the bottom of the smoke-box C, and upwardly between the walls of said smoke-box and cylinders to the opening n above the plate K and beyond the upper 100 end of the nozzle G.

The above-described construction can be used for either single or compound engines; but the necessity of a compound engine will

not appear by using a long-stroke cylinder, as a high degree of steam expansion is obtained and mechanism simpler than a compound engine can be used.

5 Having now fully described my invention, I claim—

1. In a locomotive the combination of the boiler and its smoke-box at the front end, cylinders and valves therefor having their top 10 surfaces on a lower level than the bottom of said boiler the said smoke-box completely surrounding said cylinders and valves, whereby the products of combustion are conducted downwardly around said cylinders and valves

15 substantially as described.

2. The combination of a portable steam-boiler and its smoke-box at the front end, cylinders and valves therefor having their top on a lower level than the bottom of said 20 boiler, the said smoke-box completely surrounding said cylinders and valves, whereby the products of combustion are conducted

downwardly along one side of each cylinder and valve, thence under the cylinder, and upwardly on the opposite side, to the smoke-stack substantially as described. 25

3. The combination of a portable steam-boiler and its smoke-box at the front end, cylinders and valves therefor on a level below the bottom of the boiler and completely 30 surrounded by said smoke-box, with smoke-flue dampers in said box, the products of combustion being conducted downwardly within said smoke-box to one side of the cylinders and valves, and thence upwardly on 35 the opposite side, to the smoke-stack substantially as described.

In testimony whereof I affix my signature in presence of two witnesses.

SPENCER OTIS.
